UNITED STATES PATENT OFFICE.

BENJAMIN J. BRAGDON, OF BELOIT, KANSAS.

WINDMILL.

SPECIFICATION forming part of Letters Patent No. 257,649, dated May 9, 1882.

Application filed January 4, 1882. (Model.)

To all whom it may concern:

Be it known that I, BENJAMIN J. BRAGDON, of Beloit, in the county of Mitchell and State of Kansas, have made a new and useful Improvement in Windmills, of which the following is a full, clear, and exact specification.

This invention relates to certain improvements in the construction and arrangement of the vanes of vertical windmills, whereby the mill will regulate itself according to the velocity of the wind and the work being done by the mill, as will be hereinafter fully described and claimed.

Reference is to be had to the accompanying drawings, forming part of this specification, in which similar letters of reference indicate corresponding parts in all the figures.

Figure 1 is a sectional elevation of my improved windmill, taken on the line *x x* of Fig. 2. Fig. 2 is a cross-sectional elevation of the same, taken on the line *y y* of Fig. 1; and Fig. 3 is a plan view with the connecting-rods and governors removed.

The shaft *A* is pivoted vertically in the frame 25 of the mill between the adjustable heads *a a*, and is provided with the fixed collars *b b*, which carry the radial arms *c c c* and *c' c' c'*, which arms are formed with the curved side arms, *d d d* and *d' d' d'*, which act as inside 30 stops to the windward edges or sides of the vanes, wings, or sails *D D' D''*, which are hinged centrally to the ends of the said radial arms *c* and *c'*, as shown in Figs. 2 and 3, by means of the tie-rods *e e e*, which pass through 35 the arms and suitable lugs formed on the inside of the wings or vanes.

The wings or vanes *D D' D''* are preferably made of sheet metal, and are regularly curved in cross-section, as shown in Figs. 2 and 3, 40 and they are each provided upon the inside near their edges with the eyes *f f*, in which eyes the connecting-rods *g g g* are placed in such manner as to connect the windward edge of the wing *D* to the leeward edge of the wing 45 *D''*, the windward edge of the wing *D'* to the leeward edge of the wing *D*, and the windward edge of the wing *D''* to the leeward edge of the wing *D'*, as shown in Fig. 2, and each 50 of the wings is provided at its leeward edges with the eyes or sleeves *f'*, through which the rods of the governors *h h h* pass. These governors are suspended by the rods *i* from the upper collar, *b*, on the shaft, and serve, through their weight and the centrifugal force obtained 55 by the revolution of the mill, to automatically

open and close in the windward edges of the wings, and thus regulate the amount of wind admitted to the wings in proportion to the velocity of the wind and the load upon the mill.

In order to stop the mill when desired, I provide the shaft at its lower end with the collared sleeve *E*, to which is attached the lower ends of the connecting-rods *j j*, which connect at their upper ends with the wings in such manner that by pulling down upon the rod *k*, which is fitted over the collar of the sleeve, the wings will be drawn in against the curved arm *d*, in which position the wind will be entirely excluded from the wings, and the mill will thus remain at rest.

I do not confine myself to the use of three vanes, as shown in the drawings, as any number of vanes may be used, according to the size of the wheel.

Having thus described my invention, I claim as new and desire to secure by Letters Patent—

1. The curved vanes or wings *D D' D''*, centrally hinged to the arms *c c'* and connected together by the rods *g*, substantially in the manner and for the purposes set forth.

2. The arms *c* and *c'*, formed with the curved arms *d* and *d'*, in combination with the wings or vanes *D D' D''*, hinged to the arms *c* and *c'*, substantially as described.

3. The combination, with the centrally hinged and joined wings or vanes *D D' D''*, provided with the eyes *f'* on their leeward edges, and the fixed upper collar, *b*, of the shaft *A*, of the governors *h i*, hinged at their upper ends to the said collar and passing through the eyes *f* of the vanes, substantially as and for the purpose set forth.

4. The combination, with the arms *c*, provided with the curved arms *d* and the vanes *D D' D''*, hinged to the said arms, of the sliding collar *E*, the connecting-rods *j*, and the operating-rod *k*, substantially as shown and described, whereby the said wings will be drawn in against the curved arms, as and for the purpose set forth.

5. The curved vanes or wings *D D' D''*, centrally hinged upon the tie-rods *e*, in combination with the rods *g g g* and the curved arms *d*, the rods connecting the windward edges of the wings with opposite leeward edges thereof, substantially as described.

BENJAMIN J. BRAGDON.
